COMBINED INSULATING BUSHING AND TRANSFORMER

Application filed December 1, 1930. Serial No. 499,143.

This invention relates to high tension insulating bushings having means by which power at low potential can be derived from the potential of the line connected with the 5 high voltage terminal of the bushing for the operation of relays, measuring devices, synchronizing indicators and the like.

Heretofore small amounts of low voltage power have been obtained from a high tension insulating bushing by utilizing the electrostatic capacity between selected conducting parts of the bushing. The amount of power, however, that is obtained in this way is wholly inadequate to perform all the operations desired and for which an electromagnetic transformer as a separate apparatus is now required.

It is an object of the present invention to provide a novel construction for an insulating bushing having means by which an abundance of low tension power can be derived from the high tension line which is connected to the bushing. In carrying out this object of the invention the voltage drop 25 between the high tension terminal and the ground flange of the bushing is divided between a plurality of reactance units and the primary winding of an electromagnetic transformer all of which are connected in series and are included in the insulating enclosing shell of the bushing. This arrangement permits the use of a relatively low voltage transformer, the insulation of which presents no particular difficulty.

30 A further object of the invention is the provision of a voltage transformer, suitable to be incorporated in a high tension insulating bushing having capacity means to correct the phase angle of the secondary low potential power.

A still further object is generally to improve the construction and performance of insulating bushings having auxiliary low 45 potential terminals.

Fig. 1 is an elevation partly in section of a high tension insulating bushing embodying the invention.

Fig. 2 is a section taken on line 2—2 of 50 Fig. 1.

Fig. 3 is a diagrammatic view of the potential transforming elements of Fig. 1.

Fig. 4 is a sectional detail of a modified construction of reactor units.

Fig. 5 is an elevation partly in section of a 55 potential transformer constructed in accordance with the invention.

Fig. 6 is a section along line 6—6 of Fig. 5.

Fig. 7 is a diagrammatic view illustrating the potential transforming elements of Fig. 5. 60

As shown in Fig. 1 of the drawings the potential transforming device embodying the invention is embodied in a high potential insulating bushing comprising an upper insulating section 10 which is provided with external insulating capes 12, a lower externally corrugated insulating shell 14, and an intermediate metal connecting sleeve 16 of somewhat larger diameter than said shells which comprises the support for said upper and lower insulating shells and also for the bushing. Said sleeve 16 is accordingly formed with a lower horizontal inwardly directed flange 18 to which the attaching collar 20 of said lower insulating shell is secured by means of bolts 22, a packing ring 24 being provided between the confronting surfaces of said flange and collar. An annular attaching collar 26 is secured to the lower end of the upper insulating shell by a body of cement 28 and is provided with a bottom flange 30 which extends inwardly to provide a support for a packing ring 32 on which the lower end of said insulating shell rests and outwardly beyond said collar to provide a 70 cover for the open upper end of said sleeve. Bolts 34 extend through said flange 30 and an upper outstanding flange 36 of said sleeve which latter flange is adapted to support the insulator in the casing wall 38 of an electric switch or transformer. Suitable packing 40 is interposed between the confronting faces of said flanges 30 and 36 whereby to provide a breakable fluid tight joint thereat.

75 A tubular current conducting stud 42 is extended axially through said bushing and beyond the ends thereof and is rigidly affixed at its lower end to the bottom of said lower insulating shell 14. To this end a tubular metal sleeve 44 is united with said stud 80

85 A tubular current conducting stud 42 is extended axially through said bushing and beyond the ends thereof and is rigidly affixed at its lower end to the bottom of said lower insulating shell 14. To this end a tubular metal sleeve 44 is united with said stud 90

95 A tubular current conducting stud 42 is extended axially through said bushing and beyond the ends thereof and is rigidly affixed at its lower end to the bottom of said lower insulating shell 14. To this end a tubular metal sleeve 44 is united with said stud 100

at its lower end which is provided with an upper flange 46 which overlies the bottom wall of said shell. An outer metal ring 48 is affixed to said sleeve beneath said shell 5 whereby to secure the stud permanently in the bushing at its lower end. A metal collar 50 is secured, as by cement, to the upper end of said insulating shell 12 and is provided with an outstanding attaching flange 52 on 10 which an oil reservoir is adapted to rest. Said reservoir includes an annular bottom plate 54 which rests upon said flange 52 and is secured thereto by bolts 56 having a central tubular upstanding wall 58 which closely 15 surrounds the stud 42 and provides lateral support therefor at its upper end. Radially outstanding webs 60 connect said tube 58 and bottom plate 54 between which webs passages 62 are provided which are in communication 20 with the open upper end of said insulating shell 10. An outer cylindrical housing 64 of glass is received in fluid tight manner in a groove 66 in the upper surface of said plate 54, and a cap 68 is provided through which 25 said stud extends and which forms a cover for the open top of said cylinder 64. Said cap 68 is provided with a central upstanding tubular neck through which said stud extends and a terminal cap 70 is affixed, as by 30 screw-threading, to the upper end of said stud in surrounding relation with said neck. Said stud 42 is provided intermediate its ends with a tube of insulating material 72 which may comprise a plurality of layers of 35 bakelized paper or other insulating material, and three laterally spaced concentric insulating tubes 74, 76 and 78 are suitably supported between said insulating tube 72 and the sleeve 16 of the bushing.

40 In accordance with this invention a conducting ground sleeve 80 is provided in the interior of the bushing which extends between and overlaps the confronting ends of said insulating shells 10 and 14 and encloses 45 an annular compartment 82 within the sleeve 16 in which an electromagnetic transformer is located. Said transformer comprises inner and outer cylindrical core plates 84 and 86 which are spaced apart by top and bottom 50 circular core plates 88 and 90, the abutting edges of the several core plates being arranged to interlock, whereby to provide a core path of low reluctance. A secondary winding 92 is located within said core structure adjacent the inner cylindrical plate 84 thereof and a primary winding 94 is located between said secondary winding and the outside cylindrical core plate 86, and said windings are spaced apart from each other and 55 60 from the core plates by means of the annular insulating spacers 96 whereby to insulate them from the core structure and from each other. A body of oil 98 is provided in the interior of said bushing to a level intermediate the height of the glass cylinder 64 of

said reservoir and is adapted to occupy the spaces between the transformer primary and the adjacent parts of the transformer, thus to provide a high degree of insulation for said primary winding. One lead of the primary winding 94 is brought out through said core structure and is connected with a ground terminal 100 which is provided interiorly of said sleeve 16. The other terminal 102 of said primary winding is brought out through the plate 88 of said core structure and is extended inwardly through the ground sleeve 80 for connection with the lowermost of a plurality of reactance units hereinafter to be described. At least one of the terminals of the secondary winding 92 is brought out through the side wall of said sleeve 16 to the insulated terminal 104 which constitutes the low potential terminal of the bushing, the other terminal of said secondary winding preferably being 85 grounded to the sleeve 16.

In accordance with this invention the electromagnetic transformer above described is designed to be energized at a potential considerably lower than the potential of the bushing terminal 70, since it is not desirable to insulate the primary winding 94 for such a high potential. Accordingly a plurality of serially connected reactance units are provided within the upper insulating shell along the length thereof which are included in series with the primary winding of said transformer between the grounded sleeve 16 and the high tension terminal 70 of the bushing. Said units, as shown most clearly in Fig. 3, comprise the multi-turn windings 106, carried by the inner tube 72 and similar windings 108, 110 and 112 which are supported in vertically spaced relation on and are insulated by said intermediate tubes 74, 76 and 78 respectively, the adjacent terminals of said windings being electrically connected by means of conductors 114, whereby to connect all of said windings electrically in series. The lead 114 of said lowermost reactance unit 112 is electrically connected with the ungrounded lead 102 of said transformer primary and the lead 114 of the uppermost unit is similarly electrically connected with the stud 42. As thus connected the potential drop between the high tension terminal 70 of the bushing and the grounded sleeve 16 is divided between the several reactance coils and the primary winding of the transformer, thus providing an even distribution of voltage between the several windings, and permitting the use of a transformer which need be insulated for only a small part of the total voltage of the high tension line connected with the bushing. The several reactance units may be designed to divide the voltage drop equally therebetween or where it is desired the uppermost reactance units may be wound of a higher resistance wire, whereby to assume a greater proportion of the drop.

The above described arrangement provides a voltage transformer which can be incorporated in a high tension bushing without increasing the overall dimensions of the bushing and one which does not present any difficult problems of insulation, since the voltage drop across the primary winding of the transformer can be so chosen as to be adequately insulated in the space available.

In some instances it may be desirable to provide magnetic cores for the several reactance units. Such a construction is shown in Fig. 4 in which a pair of adjacent reactance units are separated by an annular U-shaped insulating ring 116 which is loosely received on the supporting insulating tube 74. Each winding is enclosed between inner and outer concentric insulating cylinders 118 and 120, one of which, as the inner cylinder 118, has a bottom portion 122 which spaces apart said cylinders. Said cylinders 118 and 120 are wrapped about with strips of soft transformer steel 124 which constitutes a closed magnetic circuit about the winding and consequently considerably increases the reactance thereof.

In Figs. 5, 6 and 7, the invention is illustrated in connection with a potential transformer. As here shown the transformer comprises a cylindrical base portion having the upper and lower detachably connected sections 126 and 128 having the proximate outstanding annular flanges 126a and 128a through which bolts 129 extend, and the upper tubular insulating shell 130 which is provided with the external capes 132. Said upper base portion 126 has an annular inwardly directed flange 134 which carries a packing ring 135 on which the lower end of said insulating shell 132 is received and an upstanding cylindrical collar 136 which is spaced apart from the lower end of said shell to receive a body of cement 138 by which said shell is permanently secured to the base. Said shell is also provided at its upper end with an annular collar 140, which is permanently secured thereto by cement 142 and which has an annular outstanding flange 144 to which an oil reservoir is secured in fluid tight relation. Said reservoir comprises upper and lower cylindrical metal plates 146 and 148 which are maintained in spaced relation by a central upstanding tube 150 which is formed integral with said lower plate and against the upper end of which the upper end of which the upper plate 146 is arranged to bear. A cylindrical glass tube 152 constitutes the outer wall of said reservoir. Said upper and lower plates 146 and 148 are secured together by means of peripherally arranged tie bolts 154 which extend through said upper and lower plates and the attaching flange 144 of said shell. Said lower plate 148 is formed with a plurality of passages 156 which are disposed about the central tube 150

thereof and provide for free fluid communication between the interior portion of said shell and reservoir. A high tension terminal 158 is carried by said upper plate 146 and has a depending conducting stud portion 160 which projects downwardly into the insulating shell of said bushing, whereby to more evenly distribute the stress at the top of the shell.

An electromagnetic transformer 162 is located within the base portion 126 and is supported removably therein on an annular bracket 164 which is secured detachably to the inner wall of said base portion by cap screws 166. Said transformer comprises a core frame 168, a primary winding 170 and a secondary winding 172, both of which windings are located on and suitably insulated from the upper leg of the core. Leads 174 are brought out from said secondary winding and extend through an insulating bushing 176 exteriorly of said base portion and constitute the low tension terminals of the potential transformer. One lead 178 of the primary winding of said electromagnetic transformer is connected to a grounded terminal 180 of said base and the other lead 182 thereof is extended upwardly into the shell 130.

A plurality of serially connected reactors 184 are disposed within the insulating shell 130 along the length thereof. Said reactors are supported in superposed position in said shell about a central insulating tube 186 which is secured at its bottom end by bolts 188 to the tubular upstanding neck 190 of a circular plate 192. Said plate 192 has an annular flange 194 which is secured by the cap screws 195 to the lower face of the inwardly directed annular flange 134 at the upper end of said base portion 126. Annular insulating spacing members 196 of generally U-shaped section are interposed between the several reactors and serve to insulate them one from the other. The three uppermost reactor units are similarly supported on a somewhat smaller insulating tube 198 which is suitably supported by said insulating tube 186. The lead 200 of the uppermost reactor unit 184 is connected electrically with the central upstanding tubular portion 150 of plate 148 and through the upper plate 146 with the terminal 158. The terminal 202 of said lowermost reactor unit is connected to the lead 182 of said electromagnetic transformer primary. Jumpers 203 serve to connect the windings of adjacent reactor units. It will be evident that the primary winding 170 of the electromagnetic transformer is electrically connected in series with the reactors 184 between the high tension terminal 58 and the ground terminal 180. By suitably designing the reactance of the several reactors 184 the potential of the primary winding 170 of the electromagnetic

transformer can be of such value that no difficult problems of insulation are involved.

As shown in Figs. 5 and 6, the several reactors 184 are provided with magnetic cores 5 which substantially envelop the reactor windings although in some instances the core may be dispensed with or as here shown may be provided with an air gap. The cores herein shown comprise the generally annular bottom 10 portion 204, which is substantially U-shaped in cross section and is provided with a gap 205, between the upstanding U-shaped arms of which the reactance windings 184 are received, and an upper circular cover portion 15 206 having a corresponding gap 207 which is received on the upper ends of said U-shaped portion. As thus arranged the cores and the interposed insulating annular spacer members 196 constitute a supporting column for 20 the reactor units which are held in alignment by the inner insulating tubes 186 and 198.

Means are also provided to supply the 25 primary winding of the electromagnetic transformer with a leading exciting current, for the purpose of correcting the phase angle displacement resulting from the reactors 184. Said means includes a frusto-conical insulating tube 208 having a relatively thick 30 insulating wall in which a plurality of serially connected parallel condensers are arranged along the length thereof. As shown most clearly in Fig. 7, each of said condensers comprises a pair of concentric parallel plates a 35 and an intermediate overlapping plate b which is interposed between said outer plates a , the several plates of the condenser being supported and insulated from each other by the material of said tube. Each plate b is 40 common to two adjacent sets of outer plates a and thereby constitutes means for connecting the adjacent parallel condensers in series. The uppermost set of parallel plates a are connected electrically with the lead 200 45 of the uppermost reactor unit and the lowermost intermediate plate b is electrically connected with the lead 202 of the lowermost reactor unit. Each intermediate plate b is also 50 electrically connected by a conductor 210 with the conductor 203 which connects the adjacent reactor units. As thus arranged it will 55 be evident that each reactor unit 184 is shunted by two serially connected parallel condensers.

The lowermost base portion 128 is provided with a base plate which is welded to the bottom thereof and constitutes a fluid tight closure for the lower open end of the casing 60 and also provides supporting and attaching means for the transformer. A body of insulating fluid, as oil, is adapted to occupy the casing to a level intermediate the height of the reservoir at the top of the bushing, whereby to completely submerge the electromag- 65

netic transformer 162, the reactors, and the condensers above described. The insulating tube 208 is provided with a series of peripherally arranged passages 214 adjacent the lower end thereof which provide for free 70 circulation of the oil about the condenser tube 208. The oil is also free to circulate by thermal action about the electromagnetic transformer and reactor units.

The potential transformer above described 75 presents an inexpensive and reliable arrangement for deriving low potential power from a high tension line to perform the operations heretofore requiring the use of an expensive high potential electromagnetic potential 80 transformer, and is free from many of the difficult problems present in the insulation of such transformers. It is also possible to greatly improve the phase angle of the secondary low tension power by winding all or 85 certain ones of the reactance coils 184 of suitable resistance wire.

In my concurrently filed application Serial No. 499,142, I have described and claimed still another construction for obtaining the 90 voltage drop between the high tension terminal and the primary winding of the electromagnetic transformer, certain features of which are disclosed in this application.

Various modifications in the arrangement 95 and construction of the parts may be made without departing from the scope of the invention.

I claim:

1. A combined potential transformer and 100 insulating bushing comprising an outer enclosing shell, a conducting stud extended through said shell, high tension terminals at the ends of said bushing, an axial insulating tube located within said shell, a plurality of 105 reactance coils having central passages through which said tube extends surrounding and carried by and located in vertically spaced relation along the length of said tube, means electrically connecting said reactance 110 coils in series between a high tension terminal of said bushing and ground, and a low tension lead extended exteriorly of said bushing deriving its power from a selected one of said reactance coils.

2. In a potential transformer, the combination 115 of an enclosing casing comprising an upper insulating shell portion having a high tension terminal at the top and a lower metal supporting portion, a plurality of reactance 120 coils having aligned central passages arranged in superposed order along the length of said shell portion, an axial insulating tube extended through the passages in said coils and having a support at its lower end on said base portion, means electrically connecting 125 said reactance coils in series between said high tension terminal and metal support, a low tension terminal extended through and insulated from said metal supporting por- 130

- tion, and means to supply power to said low tension terminal from one of said reactance coils.
3. In a potential transformer, the combination of an enclosing casing comprising an upper insulating shell portion and a lower metal supporting base portion, an electromagnetic transformer located in said base portion having primary and secondary windings, an inner insulating tube concentric with said shell portion having a support at its lower end on said base portion and extended upwardly in said shell portion, a plurality of reactors comprising annular windings which are disposed about said tube in vertically spaced relation, annular insulating spacer members also disposed about said tube between adjacent windings of said reactors, and means electrically connecting the windings of said reactors in series with the primary winding of said transformer, said secondary winding having one of its leads extended exteriorly of said casing and constituting a low tension terminal of the potential transformer.
4. In a potential transformer, the combination of an enclosing casing comprising an upper insulating shell portion having a high tension terminal at the top and a lower metal base portion, an electromagnetic transformer located in said base portion having primary and secondary windings, an inner insulating tube concentric with said shell portion and spaced apart from the side walls thereof having a support at the lower end on said base portion, a plurality of annular reactors located on said insulating tube along the length thereof, said reactors having the windings thereof electrically connected in series with each other and with the primary winding of said transformer, the free terminal of said transformer primary having a grounded connection with said base and the free terminal of said uppermost reactor having an electrical connection with said high tension terminal.
5. In a potential transformer, the combination of an enclosing casing comprising a lower base portion and an upper insulating portion having a high tension terminal at the top, an inner insulating tube located within and spaced apart from the side walls of said insulating shell and having a support at its lower end on said base portion and a plurality of superposed reactors carried by said insulating tube along the length thereof having windings which are electrically connected in series, means to connect the winding of said uppermost reactor electrically with said high tension terminal and the winding of said lowermost reactor with said base, and a low tension lead extended exteriorly of said casing and having a power-transmitting connection with said connected reactors adjacent the base end thereof.

6. In a potential transformer, the combination of a fluid tight enclosing casing comprising a lower grounded base portion and an upper insulating portion having a high tension terminal at the top, an insulating tube extended through said insulating shell, a plurality of annular reactor units surrounding said tube and supported thereby in spaced relation from said shell, annular insulating spacing members surrounding said tube disposed between adjacent reactor units, and means electrically connecting the windings of said reactors electrically in series between said high tension terminal and said grounded base.

7. In a potential transformer, the combination of an outer enclosing casing having a lower grounded supporting portion and an upper insulating shell portion, a high tension terminal at the top of said shell portion, an insulating tube extended within said shell portion, a plurality of reactors carried by said tube in superposed relation and supported by said tube in spaced relation with said outer casing, each of said reactors comprising an annular core member through which said insulating tube extends and an annular winding associated with said core member, annular insulating members surrounding said insulating tube and disposed between adjacent reactor units, and means electrically connecting the windings of said reactors electrically in series between said high tension terminal and said grounded support.

8. In a potential transformer, the combination of an outer tubular enclosing casing comprising a lower grounded support and an upper insulating shell having a high tension terminal at the top thereof, a column of superposed annular reactors located within said casing, annular insulating spacer members located between adjacent reactor units, and an axial insulating and supporting tube extended through said annular reactor units and spacer members arranged to support them in spaced relation from the side walls of said enclosing casing, said reactor units arranged to be electrically connected in series between said high tension terminal and said grounded support.

9. In a potential transformer, the combination of an outer tubular enclosing casing comprising a lower grounded portion and an upper insulating shell portion, a high tension terminal at the top of said shell portion, a low tension terminal carried by and insulated from said grounded portion, a central insulating tube extended vertically in said shell portion having a support at its lower end on said grounded portion, a plurality of annular reactor units carried by said insulating tube along the length thereof and supported in vertical alignment by said tube, annular insulating spacer members also surrounding

said tube and interposed between adjacent reactor units, each of said reactor units comprising an annular core member having a winding thereon, means electrically connecting the windings of adjacent reactor units in series, a second insulating tube located within said shell surrounding said reactor and having metal condenser inserts embedded in and insulated from each other by the material of the tube, and means electrically connecting the condensers of said tube in shunting relation with said reactor windings.

10. In a potential transformer, the combination of an outer enclosing casing comprising a lower metal base portion and an upper insulating shell having a high tension terminal at the top thereof, a central column of superposed reactance coils located within said casing having an axial passage therethrough, an axial insulating tube extended through said passage having a support at one end, whereby to support said coils in spaced relation with the side walls of said casing, a second tube of insulating material located 20 within said casing and surrounding said column of reactance coils having spaced concentric and overlapping metal plates embedded in and insulated from each other by the insulation of the tube comprising a series 30 of vertically arranged condensers, and means electrically connecting said condensers in shunting relation with said reactance coils.

11. A high tension bushing comprising upper and lower insulating shells and an intermediate connecting ground sleeve, high tension terminals at the remote ends of said shells, a low tension terminal carried by and insulated from said ground sleeve, a conducting stud extended through said shells 40 and sleeve, an electromagnetic transformer located in said sleeve surrounding and insulated from said stud having a primary winding, one terminal of which is grounded on said sleeve, and a secondary winding, one 45 terminal of which is connected with said low tension terminal, an insulating tube extended in said upper insulating shell between said transformer and the upper high tension terminal, and a plurality of serially connected 50 reactance windings carried by said tube and electrically connected in series with said primary winding between said upper high tension terminal and the free terminal of said transformer primary.

55. 12. The combination with a bushing insulator having a grounded support, of a conductor extended through said insulator, high tension terminals at the ends of said insulator, an annular magnetic core member disposed within said insulator about said conductor, a magnetizing winding for said core member, a low tension winding located in the field of said core member having low tensioned terminals extended exteriorly of said bushing, an axial insulating tube surrounding 60

said conductor, and a plurality of serially connected reactance coils carried by said tube and electrically connected in series with each other and with said magnetizing winding between a high tension terminal of said bushing and said grounded support.

13. The combination with an insulating bushing having upper and lower insulating shell portions and an enlarged intermediate metal connecting portion, of an electromagnetic transformer located in said enlarged portion having a central passage therethrough, said transformer having a high tension primary and a low tension secondary winding, a stud extended through said bushing, high tension terminals at the ends of said bushing, an insulating tube surrounding said stud, and a plurality of reactance windings carried by said tube and electrically connected in series with the primary winding of said transformer between a high tension terminal of said bushing and ground, said transformer secondary winding having a low tension lead thereof extended exteriorly of said bushing.

14. An insulating bushing having the combination of upper and lower insulating shells, an intermediate metal connecting sleeve, an axial stud extended through said bushing, high tension terminals at the ends of said bushing, an insulating tube surrounding said stud, an annular magnetic core surrounding said tube in the vicinity of said sleeve, primarily and secondary windings associated with said core, said primary winding having one lead grounded on said sleeve, and said secondary winding having a low tension lead extended exteriorly of said bushing, a plurality of vertically spaced reactance coils carried by said insulating tube along the length thereof having their coils electrically connected in series, and means electrically connecting the uppermost reactance coil with a high tension terminal of said bushing and the lowermost coil with the other lead of said primary winding.

15. An insulating bushing having the combination of upper and lower insulating shells, an intermediate metal connecting sleeve, an axial stud extended through said bushing, high tension terminals at the ends of said bushing, an insulating tube surrounding said stud, an annular magnetic core surrounding said tube in the vicinity of said sleeve, primary and secondary windings associated with said core, said primary winding having one lead grounded on said sleeve, and said secondary winding having a low tension lead extended exteriorly of said bushing, a plurality of vertically spaced reactance coils carried by said insulating tube along the length thereof having their coils electrically connected in series, and means electrically connecting the uppermost reactance coil with a high tension terminal of said bushing and

the lowermost coil with the other lead of said primary winding, certain of said reactance coils having their windings composed of a high resistance material whereby to correct the displacement in the phase angle of said low tension secondary.

16. An insulating bushing having the combination of upper and lower insulating shells, an intermediate metal connecting sleeve, an axial stud extended through said bushing, high tension terminals at the ends of said insulating shells, a low tension terminal carried by and insulated from said sleeve, a plurality of spaced concentric insulating tubes surrounding said stud, a plurality of reactance coils carried by said tubes and arranged in superposed order along the length of said upper shell, the uppermost of said coils having the turns thereof composed of high resistance wire, means electrically connecting said reactance coils in series between a high tension terminal of said bushing and said sleeve, and a winding inductively connected with one of said coils having a connection with said low tension terminal.

In testimony whereof, I have signed my name to this specification.

GUSTAV E. JANSSON.
